Primary Examiner — Susan Bennett Hattan*Assistant Examiner* — Elizabeth S Ko(74) *Attorney, Agent, or Firm* — Barley Snyder(57) **CLAIM**

A female connector design, as shown and described.

DESCRIPTION

FIG. 1 is a front, right, top perspective view of a female connector, showing the new design;

FIG. 2 is a front, left, top perspective view thereof;

FIG. 3 is a top plan view thereof;

FIG. 4 is a front elevation view thereof, the back elevation view being identical;

FIG. 5 is a bottom plan view thereof;

FIG. 6 is a left side elevation view thereof, the right side elevation being identical;

FIG. 7 is another front, right, top perspective view of the female connector;

FIG. 8 is a front, right, bottom perspective view of the female connector;

FIG. 9 is a cross sectional view of the female connector of FIG. 7; and,

FIG. 10 is a cross sectional view of the female connector of FIG. 7.

The broken lines shown in the Figures are included to show unclaimed subject matter only and form no part of the claimed design.

1 Claim, 6 Drawing Sheets(56)
